UNITED STATES PATENT OFFICE

2,329,431

DISPENSING APPARATUS

Harold C. Bowman, Rocky River, Ohio

Application September 12, 1940, Serial No. 356,437

4 Claims. (Cl. 221—104)

This invention relates to dispensing devices, and is particularly adapted to the dispensing of powdered or finely divided solid materials.

An object of the invention is to provide an improved dispensing device which will effectively dispense finely divided materials, including those in which the particles have some tendency to pack or stick together.

Another object of the invention is to provide an improved dispensing device which may be used to dispense finely divided materials from a container in which they may be shipped or sold.

Another object of the invention is to provide an improved dispensing device which will be neat and attractive in appearance.

Another object is to provide an improved dispensing device which may be economically manufactured.

Another object is to provide an improved dispensing device which will be composed of few and simple parts.

Another object is to provide an improved dispensing device which will eliminate spaces in which finely divided material may lodge itself.

Another object is to provide an improved dispensing device which may be simply operated.

Other objects will hereinafter appear.

The invention will be better understood from the description of one practical embodiment thereof, illustrated in the accompanying drawing which shows a type of dispenser particularly intended for the dispensing of powdered soap, and in which:

Figure 1 is a front elevational view of a dispenser and an associated container, parts being broken away and shown in section;

Figure 2 is a partially elevational, partially sectional view taken in the line II—II of Figure 1;

Figure 3 is a horizontal sectional view taken on the line III—III of Figure 2;

Figure 4 is a fragmentary bottom plan view of parts appearing in the preceding figures, showing their position while discharging material;

Figure 5 is a fragmentary cross-sectional view taken on the line V—V of Figure 4; and

Figure 6 is a fragmentary sectional view taken on the line VI—VI of Figure 3.

As above indicated, the dispenser illustrated in the drawing is intended for use with a shipping or sales container, and it is further intended that the dispenser may be used with a plurality of containers of varying sizes, and with

containers which have different types of closures.

As shown in the drawing, the container itself is a cylindrical can or box 1, having at one end a closure or head 2, and at the opposite end a head 3 which is centrally perforated, the perforation normally, in transit or storage, being closed by a sheet metal cap, such for instance, as used on ordinary paint cans and on many other types of packages.

The perforated head 3 of the container is frictionally engaged by a central flange 4 formed with a main horizontal portion 5 of the framework of the dispenser. The upper end of this flange, as indicated at 6, is tapered inwardly to permit the easy insertion of the flange within the head 3 of the container.

The supporting frame is formed with an integral depending lug or flange 7, shown as slightly curved and having downwardly tapering sides which may be inserted within the channel-shaped flanges 8 of a supporting bracket 9. These flanges, as shown clearly from Figure 1, are inclined so that they converge in a downwardly direction at the same angle as do the sides of flange 7, so that the latter may be tightly wedged into place within the supporting bracket.

The bracket is perforated for the passage of screws 10 and 11 by which it may be secured to a wall W as indicated. A perforation through the depending lug 7 makes it possible to pass the screw 11 through both this lug and the bracket plate 9, to prevent ready removal of the dispensing device from the wall.

If, however, it is desired that the dispenser be readily removable without taking out the screw 11, this screw may be inserted before the dispenser is placed over the bracket, its head then being as indicated in dot-and-dash lines at 12.

It will be noted that the curved shape of lug 7 permits the heads of the screws 10 and 11 to be positioned between this plate and the flat bracket plate 9, while holding the flanges 8 tightly against the wall.

A disk 13 is used to close the bottom of the opening in the frame surrounded by the flange 4, and may, for convenience in fastening, be provided with a marginal flange 14 which may be telescopically received within the flange 4.

The disk 13 may be secured to the frame by welding, brazing, soldering, or the like, either between the disk proper or between its flange 14 and that 4 of the frame.

Disk 13 is provided with a perforation or outlet opening 15 through which material may pass to the measuring part of the dispenser.

This consists of a generally channel-shaped plunger having a flat horizontal top or web 16 and depending side flanges 17 integral therewith.

The web is perforated and formed into a depending cylindrical flange 18 which may be brought into alignment with the perforation or opening 15, above mentioned.

The ends of the web are turned downwardly to provide at one end an operating handle 19 and at the other end a lug 20 having a projecting boss 21 struck therefrom.

This boss is in horizontal alignment with a similar boss 22 struck from lug 19; and between the two bosses is positioned a helical compression spring 23.

The plunger is supported by a channel-shaped stirrup consisting of a horizontal web 24 and side flanges 25. At the upper edge of these flanges are lugs 26 which pass through slots in disk 13 and are bent over to retain the stirrup or plunger support in place.

The plunger carries an agitating member for stirring up the contents of the container, should these attempt to pack together, which is shown as a loop 27 of wire, or similar material, which extends horizontally above disk 13, and has two downwardly bent ends 28 which pass through perforations in the top of web 16 of the plunger immediately at the outer edge of the depending flange 18.

These ends have struck therefrom small projecting lugs 29, such as produced by a blow of a cold chisel. The lugs 29 are arranged to be held beneath the end of the flat leaf spring 30 secured, as by spot welding, to the underside of web 16.

It will be apparent that the agitator may be simply inserted by passing its ends through the holes in web 16 and pressing them downwardly, so that the lugs 29 snap under the end of the spring 30, after which the agitator is held firmly in place by the pressure of this spring forcing the ends 28 against flange 18.

Notches 31 may be formed in head 13 to permit any desired length of travel of the agitator, and consequently, the plunger.

Similarly, a notch 32 may be formed in the web 24 to permit the contents of the recess or space within flange 18 to drop after any desired length of travel of the plunger.

Steps 33 are formed on side flanges 17 adjacent the outer end of the plunger to limit its inward motion by contact with the edge of web 24, while its outward motion is limited by ends 28 of the agitator striking disk 13.

The operation of the device will be readily apparent from the above description and the drawing.

The user has merely to press the flange 19 toward the wall, material having previously fallen through opening 15 into the recess defined by flange 18, and as the plunger is moved, this flange is carried out over notch 32, at which point the material may drop freely from the device under the influence of gravity.

The material is all delivered at one place, without the necessity for any discharge hopper, funnel or the like.

As the plunger is moved, aperture 15 is closed by the passage of web 16 thereacross, as indicated in Figures 4 and 5.

During this motion the loop 27 of the agitator stirs the material within the container, and this

stirring is continued on the return of the plunger to its outermost position, so that the material can drop freely into the space within flange 18.

The reciprocating action of the agitator moves the material within the container to the discharge opening 15, so that substantially all of this material may be dispensed, and only a thin layer of it will remain upon the top of disk 13. Thus it eliminates the necessity for any inclined baffles or hopper-like constructions to cause the material to flow obliquely to the discharge opening.

Instead of the specific type of container illustrated, it will be apparent that any can or box consisting of a cylindrical tube and having a removable cap, or the like, might be used, and that the cylindrical tube itself might directly engage the surface of flange 4. Thus it will be apparent that this flange may be used with container of substantially different diameters, provided only that the openings to the same are of the same diameter.

The container, of course, may be of any desired material such as cardboard, sheet metal, or the like.

All parts of the device may be easily fabricated from sheet metal, with the exception of the spring 23 and agitator 27 and 28, both of which may simply be made of wire.

The parts may be assembled with only one, or at the most two, welding, soldering, or brazing operations.

The entire space within the bottom of the plunger is open to permit any particles of material which may find their way into the same to drop at one end or the other of the supporting stirrup, and similarly, there is no part so situated that it may retain material in position to reach the spring and obstruct its operation.

The dispenser may be easily removed from the wall bracket and inserted in the opened upper end of the container, and the assembled container and dispenser then inverted and returned to the wall bracket, without affording the material any opportunity to spill.

While I have described the illustrated embodiment of this invention in some particularity, obviously many modifications and variations will readily occur to those skilled in the art to which it appertains, and I do not, therefore, limit myself to the precise details shown and described, but claim as my invention all embodiments, modifications, and variations coming within the scope of the appended claims.

I claim:

1. In a dispenser, a sheet metal plunger of generally channel-shaped cross-section having a perforation formed therethrough and being formed about said perforation into a depending peripheral flange, an agitator carried by the plunger comprising a loop of wire having two downwardly extending ends passing through the web of the plunger and bearing against the exterior of the peripheral flange, and a retaining spring pressing said ends against said flange and secured within the hollow of the plunger.

2. In a dispenser, a sheet metal plunger of generally channel-shaped cross-section having a perforation formed therethrough and being formed about said perforation into a depending peripheral flange, an agitator carried by the plunger comprising a loop of wire having two downwardly extending ends passing through the web of the plunger and bearing against the exterior of the

peripheral flange, and a retaining spring pressing said ends against said flange and secured within the hollow of the plunger and a projection on each of said depending wire ends, the projections engaging the retaining spring.

3. A dispenser comprising a sheet metal frame consisting of a generally horizontal plane top and a substantially vertical supporting lug, the top being centrally perforated and formed at the periphery of the perforation into an upstanding peripheral attaching flange, a disk spanning the perforation with its undersurface in substantially the plane of the undersurface of the horizontal portion of the frame securing means holding said disk to the frame.

4. A dispenser comprising a sheet metal frame consisting of a generally horizontal plane top and

a substantially vertical supporting lug, the top being centrally perforated and formed about the perforation into an upstanding marginal flange having a contracted upper edge, a disk spanning the perforation, a discharge opening formed through the disk, a sheet metal plunger underlying the framework and the disk and having a material receiving recess adapted to be brought into alignment with the discharge opening, resilient means holding said plunger with its recess underlying the opening and a channel-shaped stirrup supporting the plunger and secured to the disk, the plunger covering the bottom of the recess when the latter is in alignment with the opening.

HAROLD C. BOWMAN.
